UNITED STATES PATENT OFFICE.

LEVI B. REAMS, OF CASSOPOLIS, MICHIGAN.

WAGON-JACK.

SPECIFICATION forming part of Letters Patent No. 475,021, dated May 17, 1892.

Application filed March 2, 1892. Serial No. 423,537. (No model.)

To all whom it may concern:

Be it known that I, LEVI B. REAMS, a citizen of the United States, residing at Cassopolis, in the county of Cass and State of Michigan, have invented certain new and useful Improvements in Wagon-Jacks, which improvements are fully set forth and described in the following specification, reference being had to the accompanying sheet of drawings.

10 The object of this invention is to provide a jack which shall be simple in construction, which can be easily adjusted to operate with axles of varying heights, and which may also serve when in use as a rack on which the 15 wheel may be hung during the operation of oiling.

In the annexed drawings, Figure 1 is a perspective view of my improved jack, showing the same in position for use. Fig. 2 is a side 20 elevation of said jack and shows the same in the position which it assumes when not in use. Fig. 3 shows the same in the position necessary to elevate an axle in order to raise a wheel from contact with the floor or ground.

25 Referring to the drawings, the letter *a* denotes the base or foot of the complete jack, and *b* two uprights located on the base *a* and projecting upward therefrom. These uprights *b* may be greatly strengthened by locating on 30 the foot *a*, between the same, a block *a'*, to which the uprights may be rigidly fastened.

Pivoted at *b'*, between the upper extremities of the uprights *b*, is an arm *c*, which, as illustrated in Fig. 2, extends for a short distance substantially at right angles with the above-mentioned uprights *b*. Arm *c* is then bent downward and extends in a direction parallel with the uprights *b*, as shown in Fig. 2, such parallel portion being denoted by reference-letter *c'*. Arm *c* is then bent inward at right angles with portion *c'* and parallel with the first-described portion of the arm. Arm *c* as a whole is shaped substantially as the outline of a rectangle, with one of its longer 45 sides removed, the exact shape of the same being clearly seen in any of the figures of the annexed drawings. The free end of arm *c* is pivoted to the end of the operating handle or lever *d*, which lever is hung in bearings 50 at *e* between two sliding blocks *f*. These blocks *f* are located the same distance apart as the uprights *b*, and are arranged to slide

a limited distance, when properly actuated, on the edges of the said uprights. Assuming now that I have a jack in the position shown in Fig. 2, it will readily be seen that when the operating handle or lever *d* is forced downward the arm *c*, hinged between the uprights *b*, will be caused to swing on its pivot *b'*, the arm swinging outward and slightly upward. 60 As the downward movement of the lever *d* is continued, the blocks *f*, between which the lever is pivoted, ride slowly downward on the edges of the uprights *b*, until the point *e* (where the lever is pivoted) passes below the arc of 65 the circle described by the free end of the arm *c*. (See Fig. 3.) When this position is reached by point *e* on blocks *f*, it will be readily understood that any pressure on arm *c* calculated to force the said arm inward (toward the uprights) will serve to throw and hold the end of the operating-lever *d* firmly 70 against the floor or ground, consequently holding arm *c* in its outward and elevated position. (See Fig. 3.) An arm *g* is provided, one 75 end of which is formed with a hub *g'*, which is bored to fit loosely upon portion *c'* of arm *c*. The outer or free end of arm *g* is grooved or spoon-shaped, as at *h*, for a purpose herein-after explained. 80

Assuming now that I have a complete jack of the form described and it is desired to use the same during the operation of oiling the axles of a vehicle, the jack is first placed directly in front of the wheel to be oiled (see 85 Fig. 1) and the nut having been removed from the axle the arm *g* is adjusted on portion *c'* of arm *c* until the threaded end of the axle lies in the grooved end of the said arm *g*. The tendency of the arm *g* to slip downward 90 upon portion *c'* after adjustment will cause the hub on the end of arm *g* to cramp upon portion *c'*, thus holding it in the desired position in which it had been previously placed. Pressure is now applied to lever *d*, causing 95 arm *c* to swing slightly outward and upward until the point *e* has passed below the arc described by the free end of arm *c*, as above explained. When arm *c* swings outward and upward, it naturally carries with it the arm *g*, 100 above described as having been adjusted under the end of the axle. When arm *g* is carried upward, it raises the end of the axle with it, thus lifting the wheel from the floor or

ground. The wheel may then be slipped from the axle of the vehicle onto the arm *g*, as shown in dotted lines, Fig. 3, where it may remain while its axle is being cleaned and oiled, thus avoiding the necessity of lifting the wheel from the axle and replacing the same, which task in the case of heavy and muddy wheels is often a very disagreeable and laborious one. After oiling the axle and returning the wheel to place thereon the lever-handle *d* is raised to the position shown in Fig. 1, permitting the wheel to rest on the ground or floor, when the jack may be removed and the nut again screwed on the axle end. My device as a whole is of simple and cheap construction, is adjustable for use with axles of

different heights, and provides sufficient power to readily raise the heaviest vehicle.

Having described my invention, I claim—

In a wagon-jack, in combination with suitable uprights, a bar hinged therein having a laterally-projecting arm *g* with cupped end and an operating-handle connected with the free end of said bar, as set forth, and blocks *f*, located and arranged to slide upon the uprights in which said handle is fulcrumed, as and for the purpose specified.

LEVI B. REAMS.
